ARTHUR C. LINDHOLM, OF SPRINGFIELD, MASSACHUSETTS.

RESEATING ATTACHMENT.

1,392,585.

Specification of Letters Patent.

Patented Oct. 4, 1921.

Application filed June 24, 1920. Serial No. 391,378.

To all whom it may concern:

Be it known that I, ARTHUR C. LINDHOLM, a citizen of the United States of America, and a resident of Springfield, in the county 5 of Hampden and State of Massachusetts, have invented a new and useful Reseating Attachment, of which the following is a specification.

My invention relates to improvements in 10 devices for reseating, recutting, or regrinding valve-seats in internal-combustion engines and the like, and consists essentially of a certain peculiar, portable, cutting element, which is adapted to have connected 15 therewith and to drive a reseating or cutting tool or cutter, the power being applied through a flexible shaft together with means for attaching such shaft to a fixed support, and with driving means for said 20 shaft, all as hereinafter set forth.

As is well known, the valve-seats of internal-combustion engines and the like require reseating, recutting, or regrinding from time to time, and the primary object 25 of my invention is to provide a comparatively simple and inexpensive attachment wherewith such seats can be recut or reground expeditiously, conveniently, and accurately. The cutting element of this attachment being portable, the operation of 30 reseating is enhanced to a degree not otherwise possible.

A further object is to provide an attachment 35 of this character which can be readily connected with any motor that may be located at a convenient point within range, through the medium of the flexible shaft employed as a part of said attachment, of the work to be done, that is, of the valve- 40 seats to be cut or reseated.

Other objects and advantages will appear in the course of the following description.

I attain the objects and secure the advantages of my invention by the means illustrated in the accompanying drawings, in 45 which—

Figure 1 is a side elevation of a reseating attachment which embodies a practical form of my invention, the intermediate portion 50 of the flexible shaft being broken out; Fig. 2, an end elevation of the bracket through the medium of which connection with the motor is made; Fig. 3, a horizontal section through the cutting element, the outer portions of the handles being broken 55 off; Fig. 4, a vertical section through said

cutting element, taken on lines 4—4, looking in the direction of the associated arrow, in Fig. 3, and, Fig. 5, a rear elevation of the cutting element, without the handles and 60 the flexible shaft, and the cutter and its spindle being omitted.

Similar reference characters designate similar parts throughout the several views.

In Fig. 1 an electric motor is represented 65 at 1, and a bed-plate therefor at 2. These members may be parts of a portable grinding machine, or of any other machine suitable for the purpose, or they alone may be especially provided for the purpose, but in 70 any event should be located or capable of being located at a convenient distance from the work to be done. The motor 1 is provided with a driving shaft 3 upon which is mounted a driving gear 5. The motor 1 75 is located adjacent to one edge of the bed-plate 2 so as to present the gear 5 in convenient position for driving the revoluble members of the attachment. Such location is not imperative, however, inasmuch as certain of the driving or driven members, or 80 both, may be lengthened, or intermediate transmission members employed. A horizontal stud 6 is set in the bed-plate 2 and protrudes beyond one edge thereof, and said 85 stud is secured in said bed-plate by means of a bolt 7 tapped into said plate over said stud. The stud 6 is parallel with the motor shaft 3, and properly located relative thereto, as will hereinafter appear. 90

A bracket 8 has its base mounted on the protruding part of the stud 6, such base abutting the contiguous edge of the bed-plate 2. The aforesaid base of the bracket 8 is in the form of a split sleeve 9 having 95 a pair of laterally-extending lugs or ears 10 bored and tapped to receive a bolt 11. The sleeve 9 fits on to the stud 6, and the bolt 11 when tightened clamps the parts so that the bracket 8 is held immovably in 100 place on said stud. The bracket 8 stands vertically, and is provided on top with a bearing 12 and a split sleeve 13. The sleeve 13 has a pair of upwardly-extending lugs or ears 14. A horizontal shaft 15 is journaled in the bearing 12, which latter is at the inner end of the top portion of the bracket 8, and secured on the inner, protruding terminal of said shaft is a gear or pinion 16 which intermeshes with the motor gear 5. 110

A flexible shaft of ordinary construction,

comprising a non-rotary sheath 17, and a revoluble member 17^a (Fig. 3), is employed in this attachment. One end of the flexible-shaft member 17^a is attached to the shaft 15 in the usual manner or by any suitable means, while the corresponding end or terminal of the sheath 17 is inserted in the sleeve 13 and clamped therein by means of a bolt 18 which is inserted in the ears 14, 10 the latter, like the ears 10, being bored and tapped to receive said bolt. Thus it is seen that the revolving member 17^a of the flexible shaft can be driven by the motor 1 through the medium of the gear 5, the pinion 16, and the shaft 15.

The opposite end or terminal of the flexible shaft is connected with the cutting element of the attachment in the manner presently to be described.

20 The aforesaid cutting element comprises a casing 19 having therein a horizontal chamber 20, and from which extend a rearward projection 21 and a downward projection 22. The casing 19 is provided on top with a removable cover 23 which may be secured in place by means of screws or otherwise. Upon removing the cover 23 access is had to the chamber 20 and the parts and members therein. At the ends of the casing 19 25 are bosses or lugs 24—24 into which are inserted the inner terminals of a pair of horizontal handles 25. The handles 25 are designed to be grasped in the hands when the cutting element is in use, that is to say, these 30 handles are the members by means of which the cutting element is carried or moved about and handled or manipulated during the reseating operation.

Within the chamber 20 are an intermeshing worm 26 and a worm-wheel 27. The worm 26 is secured on a horizontal shaft 28 which is journaled in the left-hand end of the casing 19 and in the rearwardly-extending projection 21, bushings 29—29 being employed for said shaft at each end of said worm. The rear terminal portion of the shaft 26 is enlarged and has a socket 30 therein, as best shown in Fig. 5, of a shape and size to receive the inner end of a plug 31 45 which is rigidly attached to the end of the flexible-shaft member 17^a that is connected with the cutting element, such plug being flattened on two sides in the usual manner. There is a split bushing 32 in the projection 50 55 back of the shaft 28, or behind the vertical plane of the rear, enlarged end of said shaft, and the flexible-shaft sheath 17 at this end is inserted in said bushing and clamped and secured tightly therein by means of two 60 screws 33 which are tapped into the top of said projection and when tightened compress and contract said bushing on said sheath. It is now clear that the rotary motion of the flexible-shaft member 17^a is 65 imparted to the worm 26 through the me-

dium of the plug 31 and the shaft 28. The worm 26, of course, drives the worm-wheel 27.

The worm-wheel 27 is secured to the upper terminal of a spindle 34 which is journaled in the vertical projection 22, such projection extending upwardly into the chamber 20 beneath said worm-wheel to afford a support for the same. A nut 35 is provided on the upper end of the spindle 34 75 to retain the worm-wheel 27 in place or assist in so doing. The spindle 34 extends below the projection 22, and that portion of said spindle which protrudes from the bottom of said projection is enlarged to form 80 a socket 36 (Fig. 4) for the reception of the upper terminal of a cutter spindle 37, and this enlarged part of said first-named spindle has in the sides thereof oppositely-disposed, bayonet-joint slots 38, to receive a 85 bayonet-joint pin 39 which projects from opposite sides of said spindle to enter said slots and engage or be engaged by the innermost edges of the same. By means of this bayonet joint the spindle 37 is held in engagement with the spindle 34 and caused to revolve with said spindle, it being understood that the latter revolves to the left in the present instance.

A reseating tool, cutting implement, or 95 cutter 40 is secured on the spindle 37, which latter extends below said cutter and is of a size to permit the same to pass down through the opening in the valve-seat that is to be cut.

In practice, assuming that the bracket 8 be in place on the stud 6, with the pinion 16 in engagement with the gear 5, the latter is set in motion, and the cutting element in the hands of the operator, who grasps the 105 handles 25, is raised in position over the valve-seat to be cut or reseated, and the lower terminal of the spindle 37 is passed down through said valve-seat, until the cutter 40 comes into contact with said seat. The cutter, which meanwhile is revolving, 110 being driven by means of the flexible shaft and the worm drive, is pressed downwardly on to the valve-seat, and quickly cuts the same to the required degree or extent. Then 115 the cutting element is elevated to withdraw the cutter and its spindle 37 from the valve-seat, and said element is taken away to be applied to another valve-seat, or to be laid aside, in which latter event the power is shut off. The reseating operation is rendered 120 very simple by the means which I have provided, and is accomplished in the minimum amount of time, and with very little labor or effort. The valve-seats are cut with the 125 utmost accuracy by this means.

By employing a worm drive I obtain the necessary amount of power and the required degree of stability or uniformity in the driving and driven parts, and it is due to 130

these factors which in turn are due to said worm drive that I am able to obtain the accuracy and other advantages that accrue from the use of my invention.

5 A washer 41 may be placed on the spindle 34 between the enlarged, lower terminal thereof and the bottom of the projection 22.

In Fig. 5 the extension 21 and the split bushing 32 are in cross section taken on lines 10 42-42, Fig. 4.

The bracket terminal of the revoluble, flexible-shaft member 17^a may be attached to the bracket shaft 15 in a manner similar to that in which the other terminal of said 15 number is attached to the worm shaft 28.

With this attachment a valve can be "ground in" to its seat, the valve then being substituted for the cutter 40.

The terms "cutter" and "cutting" as here- 20 in employed are intended respectively to include abrading members and the act of abrading.

More or less change in the shape, size, construction, and arrangement of some or 25 all of the parts of my invention, as set forth in connection herewith, may be made, without departing from the spirit of said invention or exceeding the scope of what is claimed.

30 What I claim as my invention, and desire to secure by Letters Patent, is—

1. In a reseating attachment, a portable cutting element comprising a casing having an extension, a worm and worm shaft journaled 35 in said casing, a flexible shaft, said worm shaft having a socket in one end for the attachment thereto of one end of the revoluble member of said flexible shaft, a split bushing in said extension to receive the corresponding end of the sheath of said flexible 40 shaft, means to cause said bushing to bind on said sheath, and a worm-wheel and spindle therefor also journaled in said casing, said worm-wheel intermeshing with said 45 worm, and said spindle being adapted to have a cutter connected therewith.

2. In a reseating attachment, a portable cutting element comprising a casing having an extension, a worm and worm-shaft journaled in said casing, a flexible shaft, said worm shaft having a socket in one end for the attachment thereto of one end of the revoluble member of said flexible shaft, a split bushing in said extension to receive the corresponding end of the sheath of said flexible shaft, means to cause said bushing to bind on said sheath, and a worm-wheel and spindle therefor also journaled in said 55

casing, said worm-wheel intermeshing with said worm, and said spindle having a socket 60 therein to receive a cutter spindle, and adapted to operatively engage said last-named spindle.

3. The combination, in a reseating attachment, with a fixed member, a bracket mounted on said member, a shaft journaled in said bracket, a pinion secured on said shaft, and a flexible shaft connected with said first-named shaft and mounted on said bracket, 65 of a portable cutting element comprising a casing, a worm and worm shaft journaled in said casing, said flexible shaft being connected with said worm shaft and mounted on said casing, and a worm-wheel and spindle therefor also journaled in said casing, 70 said worm-wheel intermeshing with said worm, and said spindle being adapted to have a cutter connected therewith.

4. The combination, in a reseating attachment, with a bed-plate, a motor on said 80 plate, said motor having a shaft and a gear thereon, and a stud secured to said plate, of a bracket mounted on said stud, a shaft journaled in said bracket, a pinion on said last-named shaft and intermeshing with said 85 gear, a flexible shaft connected with said bracket shaft and mounted on said bracket, a casing, a worm and worm shaft journaled in said casing, said flexible shaft being connected with said worm shaft and mounted 90 on said casing, and a worm-wheel and spindle therefor also journaled in said casing, said spindle being adapted to have a cutter connected therewith.

5. The combination, in a reseating attachment, with a support and a motor thereon, 95 said motor having a driving member, of a bracket detachably connected with said support, a shaft journaled in said bracket and having a member to engage said driving member of said motor and being driven thereby, and a portable cutting element comprising a casing, a worm and worm shaft journaled in said casing, a flexible shaft operatively connected with said bracket shaft 100 and with said worm shaft, and a worm-wheel and spindle therefor also journaled in said casing, said worm-wheel intermeshing with said worm, and said spindle being adapted to have a cutter connected there- 105 with.
